Attorney

UNITED STATES PATENT OFFICE.

DANIEL C. WHITENACK, OF SELAH, WASHINGTON.

FRUIT-PICKING RECEPTACLE.

Application filed December 29, 1921. Serial No. 525,667.

To all whom it may concern:

Be it known that I, DANIEL C. WHITENACK, a citizen of the United States, residing at Selah, in the county of Yakima and 5 State of Washington, have invented certain new and useful Improvements in Fruit-Picking Receptacles, of which the following is a specification.

This invention relates to a fruit picking 10 receptacle and it has for its object to provide an improved article of this nature constructed in such manner that it may be easily handled and will deliver the fruit to other receptacles with a minimum of bruising 15 or other damage.

Further objects and advantages of the invention will be set forth in the detailed description which follows.

In the accompanying drawing:

20 Fig. 1 is a front elevation of a fruit-picking receptacle constructed in accordance with the invention.

Fig. 2 is a vertical sectional view therethrough.

25 Fig. 3 is a plan view thereof.

Fig. 4 is a fragmentary sectional view through the upper edge of the receptacle, and

Fig. 5 is a fragmentary sectional view 30 through the lower portion of the receptacle.

Like numerals designate corresponding parts throughout the several figures of the drawing.

The receptacle comprises a sheet metal 35 sheath or casing 5, having a convex front wall 6 and a concave rear wall 7, said concave rear wall conforming to the curvature of the body of the picker. The lower front wall of the sheath 5 is cut away, as indicated at 8, so that the lower folded portion 9 of a bag or lining, 10 may pass therethrough without interfering with the resting of the entire structure and its contents upon the lower edge of the casing 5. The 40 upper edge of the bag 10 is folded over the upper edge of the sheath 5 and is secured by a retaining wire 11. At the juncture of the side walls of the bag 10 and the bottom of said bag a wire 12 is inserted. The bottom 45 10^a of the bag, together with an extension 10^b of the front wall of the bag constitutes the folded over portion or spout 9. A cord or like flexible connection, 13, is se-

cured to the free edge of the lower side of the spout 9 and its bight portion is adapted 55 to be engaged by a snap hook 14, which is secured at 15 to the front wall of the sheath 5. A strap 16 is secured to the ends of the casing as indicated at 17 and this strap is adjustable as to length, through the medium 60 of a buckle 18.

I am aware of the fact that it is not broadly new to provide a fruit-picking receptacle having an open bottom through which the contents may be discharged, nor 65 to provide such a receptacle with a metallic sheathing and a fabric lining. However, the present invention possesses several features of very great importance over known devices of this nature among which may be 70 mentioned the following:

1. The casing 5 is wider at the bottom than at the top. Thus the fruit discharged therefrom falls in bulk instead of having a rolling motion imparted thereto, which rolling motion causes bruising and stem punctures.

2. The metallic sheathing may rest upon the ground floor, or other support while the bottom of the bag is held free of the ground or floor. Thus all of the weight is taken by the casing and none of it is brought upon the fruit. This is due to the fact that the bottom of the bag 10 is at a higher level 80 than the bottom of the casing 5.

3. The snap hook and supporting strand 13 are so arranged that the strand may be released from the snap hook with one hand by pressing downwardly upon the thumb piece 19 of the snap hook, and using the fingers of the same hand to disengage the strand 13 from the hook. This leaves the other hand free to arrange the boxes or other receptacles into which the fruit is to be discharged.

4. The concave rear wall of the sheathing 5 permits the structure to conform to the body of the user, and this fact in conjunction with the fact that but a single strap is employed renders it possible for the user to shift the structure as a whole to varying positions, easily and quickly, to avoid limbs and other obstructions.

It is to be understood that the invention is not limited to the precise construction set forth, but that it includes within its pur-

view whatever changes fairly come within either the terms or the spirit of the appended claims.

Having described my invention, what I claim is:

1. A fruit-picking receptacle comprising a metallic sheath wider at the bottom than at the top, a fabric lining therein constituting a bag and a discharge spout constituted by an extension of the fabric lining and extending laterally beyond the side of said receptacle at a point above the level of the bottom of said sheath, the bottom of the bag lying wholly above the lower edge of said sheath until said spout is released to discharge the contents of the bag.
2. A structure as recited in claim 1 in combination with means for drawing the end of said spout upwardly on the outside of said sheath.
3. A structure as recited in claim 1 in combination with means for drawing the end of said spout upwardly on the outside of said sheath and for holding the same in elevated position, said means comprising a

flexible loop engaged with the spout and a snap hook carried by the sheath and operable to release the same by a downward pressure of the thumb thereon.

4. A device of the character described comprising a sheet metal receptacle open at the top and bottom and wider at the bottom than at the top and having a portion of one of the side walls cut away adjacent the lower edge thereof, a fabric lining in said receptacle and secured to the upper portion of the receptacle for constituting a bag, the side walls of the said bag being extended at the bottom through the cutaway portion above the level of the lower edge of the receptacle of the casing to constitute a spout and means upon the exterior of the receptacle for holding said spout in elevated position.

In testimony whereof I affix my signature in the presence of two witnesses.

DANIEL C. WHITENACK.
